OSCILLATING SUCTION BOX

William P. Muir, Montreal, Quebec, Canada, assignor to Dominion Engineering Works Limited, Montreal, Quebec, Canada, a corporation of Canada

Application October 21, 1931. Serial No. 570,058.

17 Claims. (Cl. 92—51)

This invention relates to a suction box assembly for Fourdrinier machines and particularly to an assembly in which the boxes are moved back and forth across the sheet forming wire at a continuously changing angle.

The principal object is to provide an assembly in which the desired movement of the boxes is accomplished without imposing appreciable reversal shocks on the box supporting and operating means and one in which the frictional resistances, tending to oppose movement of the boxes, are reduced to a minimum.

The salient feature of this invention resides in moving each end of the individual boxes in a continuous or circular path about a fixed axis, the arrangement provided for this purpose being characterized in that each end of the box has a unidirectional movement about its own axis which is preferably opposite to the unidirectional movement of the companion end so that the box, as a whole, is moved back and forth across the wire at a continuously changing angle. This arrangement eliminates the imposition of reversal shocks on the box supporting and operating means since the change in the direction of movements of the boxes with respect to the wire is accomplished without changing the direction of movement initially imparted to the ends of the boxes by the operating means. Consequently, with this arrangement, it is not necessary to provide an automatic reversing motor since the continuous or circular movement of the ends of the boxes about fixed axes enables the desired movement to be imparted to all of the boxes through the medium of a unidirectional drive shaft. A further advantage of the described arrangement is that it facilitates the reduction of frictional resistances opposing the movement of the boxes and enables such movement to be effected with a minimum expenditure of power. The actuation of the boxes so that each end moves about its own axis in a direction opposite to that of the companion end is important, in that it provides for a continuous and substantial change in the angular position of the boxes with reference to the wire during the back and forth movement. It is, however, considered within the scope of this invention to arrange the boxes so that each end moves in the same direction as the companion end. All of the boxes may be simultaneously moved in the same direction or the arrangement may be such that each box is moved in a direction opposite to certain of the remaining boxes. The last arrangement is particularly desirable since the opposed movements of the

boxes tends to prevent lateral displacement of the wire.

Proceeding now to a more detailed discussion of the invention reference will be had to the accompanying drawings, wherein—

Figure 1 is a side view partly in section of a suction box assembly provided in accordance with this invention.

Figure 2 is a transverse sectional view taken along the line 2—2 of Fig. 1.

Figure 3 is an enlarged sectional view through one of the suction box supports, said view being taken substantially along the line 3—3 of Fig. 2.

Figure 4 is a side view similar to Fig. 1 but looking towards the opposite side of the assembly.

Referring more particularly to the drawings, 11 designates a series of suction boxes equipped with the usual perforated covers 11a. Each box is carried by a pair of supporting pins 12 having

their lower extremities attached to opposite end portions of the cover 11a by means of plates 14, each plate being provided with a pin receiving opening 15 and a recess 16, the latter receiving an enlarged head 12a formed at the lower end of the pin.

The pins are held against turning movement in the openings 15 and the plates 14 are rigidly fastened to the box cover 11a in any suitable manner. Each pin 12 is rotatably mounted in a supporting sleeve 17 which is eccentrically apertured to provide the pin receiving bore 18.

The upper end of the pin projects above the sleeve and is supported therefrom by means of an interposed anti-friction bearing comprising an inner race 19, an outer race 20 and a series of intervening rollers 21. The inner race 19 is in the form of a tapered cone surrounding the upper portion of the pin beneath the retaining washer 22 and the nut 23. The outer race 20 is in the

form of a ring having its inner face tapered to conform to the taper of the cone 19 and is mounted in a recessed annulus 24 suitably secured to the upper end of the sleeve 17. At the lower end of the sleeve the pin receiving bore 18 is enlarged to provide a recess receiving the bushing 25 and suitable packing 26. Above the bushing 25 the bore 18 and the pin 12 are preferably formed with complementary tapering portions 18a and 12a respectively.

Each sleeve 17 is mounted to revolve in one of a pair of longitudinally extending casings 28, these casings 28 being supported at their ends on pedestals 29 rising from the side frames 30. To

this end an inner ball race or cone 31 is fitted on the upper portion of the sleeve beneath the pin supporting annulus 24, said cone or ball race 31

surrounding a reduced portion of the sleeve and resting on a shoulder 32. A series of anti-friction rollers 33 are interposed between the inner race 31 and an outer race 34, the latter being fitted in an opening defined by the depending flange 34a of a circular plate 34b. The plate 34b carries a dome shaped cover 35 enclosing the upper ends of the sleeve 17 and pin 12 and is mounted on the removable top portion 28a of the casing 18, said top portion 28a being formed with an opening 28b receiving the flange 34a. At some distance from its lower end the sleeve 17 is formed with an outwardly projecting shoulder 36 supporting a gear 37 which is keyed or otherwise fixed to the body of the sleeve. The sleeve is supported at its lower end by a ball bearing comprising an inner race 38, an outer race 39 and a series of anti-friction rollers 40. The inner race 38 is in the form of a tapered cone surrounding the lower portion of the sleeve and fitting against the lower surface of the shoulder 36. The outer race 39 is in the form of a ring having its inner surface tapered to conform to the taper of the rollers 38. This outer race or ring 39 is mounted in a depending circular portion 28c of the casing 28 and is supported on the upper edge of a ring shaped member 41. The outer periphery of the ring 41 is stepped to provide a shoulder 42 engaging a complementary supporting shoulder 43 formed at the lower end of the casing portion 28c. The inner periphery of the ring 41 is also stepped to provide a supporting shoulder 44 on which is arranged a suitable packing 45 interposed between said ring shaped members and the adjacent surface of the sleeve. The series of sleeves 17 supported by each casing 28 is arranged therefore so that the gear 37 of each sleeve meshes directly with the gears of the adjacent sleeve. A drive gear 46 is mounted in one end of each casing 40 28 and meshes with the gear 37 of the adjacent sleeve 17. Each drive gear 46 is fixed to the upper end of a vertical shaft 47 mounted in suitable bearings 48. A bevel gear or pinion 49 is fixed to the lower end of each shaft 47 in mesh with complementary bevel gears or pins 50 fixed to a cross shaft 51. In the present instance the cross shaft 51 is shown as consisting of a hollow tube 52 having short solid shaft sections 53 fitted in each of its opposite ends. These shaft sections 53 are formed to present reduced trunnion portions 54 projecting beyond the ends of the tube 52 and carrying the gears or pinions 50, said trunnions 54 being journaled in suitable bearing members 55 mounted in the side frames 30. One of the trunnions 54 is projected outwardly beyond the supporting side frame 30 and is coupled to the drive shaft 56 of a motor 57 through the medium of suitable reduction gearing 58. The motor 57 and the casing of the reduction gear 58 are herein shown as carried by suitable brackets 59 and 60 fastened to the side frame 30. Shaft 51 is preferably enclosed by a tubular casing 51a extending between the side frames 30.

From the foregoing it will be manifest that when the motor 57 is energized it serves to rotate each of the pin supporting sleeves 17 through the medium of the cross shaft 51, gears 50 and 49, shafts 47 and gears 46 and 37. With the particular form of gearing described herein the direction of rotation imparted to each sleeve is opposite to that of the adjacent sleeve in the same series. During rotation of each sleeve the pin mounted therein is obviously caused to move in a circular path about a fixed center coinciding with the central longitudinal axis of the sleeve.

Hence, as regards the two pins supporting the opposite ends of each box, it will be manifest that each pin has a unidirectional movement about its own axis which is opposite to the unidirectional movement of the companion pin. During this movement of the pins each box is caused to move back and forth across the sheet forming wire (not shown) at a continuously changing angle so that the wear on the engaging surfaces of the wire and boxes is distributed in a very desirable manner. The direction of movement imparted to each box is at all times opposite to the direction of movement of the adjacent box with the result that the opposed movements of the boxes tend to offset any tendency towards lateral displacement of the engaging wire.

Having thus fully described what I now consider to be a preferred embodiment of the invention, it will be understood that various modifications may be resorted to. For example, in place of the particular gearing herein described it is possible to employ various other types of gearing and to arrange the same so that the supporting pins associated with each box are moved in the same direction instead of being moved in opposite directions as previously described. It is also possible to employ a form and arrangement of gearing which will cause the same direction of movement to be imparted to all of the boxes simultaneously although it is preferred that each box be moved in a direction opposite to certain of the remaining boxes. The foregoing and various other modifications which will obviously suggest themselves from a knowledge of the present invention are considered to fall within the scope and spirit of the appended claims.

Having thus described my invention, what I claim is:—

1. In a paper making machine the combination of a suction box and means for moving the box back and forth across the wire at a continuously changing angle with respect to said wire, said means serving to move each end of the box in a continuous path about a fixed axis.

2. A suction box mounting for paper making machines comprising a pair of supporting members attached to the ends of the box and means for moving each member in an endless path about a fixed axis.

3. A suction box mounting for paper making machines comprising a pair of supporting members attached to the ends of the box and means for moving each member in an endless path about a fixed axis and in a direction opposite to the movement of the companion member.

4. A suction box mounting for paper making machines comprising a pair of supporting members, means attaching said members to the ends of the box so as to prevent angular movement of the box with respect to said members and means for moving each member in an endless path about a fixed axis.

5. A suction box mounting for paper making machines comprising a pair of supporting members attached to the ends of the box in a manner preventing angular movement of the box with respect thereto, and means for moving each member in an endless path about a fixed axis and in a direction opposite to the movement of the companion member.

6. The combination with a suction box for paper making machines of means for moving each end of the box in a circular path about a

fixed axis and in a direction opposite to the direction of movement imparted to the companion end so that the box, as a whole, is moved back and forth across the sheet forming wire 5 at a continuously changing angle with respect to said wire.

7. A suction box assembly for Fourdrinier paper making machines comprising a series of suction boxes positioned beneath the sheet forming wire 10 and means for moving the suction box back and forth across the wire at a continuously changing angle with respect to said wire, the direction of movement imparted to each box being opposite to that imparted to other boxes of the series.

15 8. A suction box assembly for Fourdrinier paper making machines comprising a series of suction boxes positioned beneath the sheet forming wire and means for moving the suction box back and forth across the wire at a continuously changing angle with respect to said wire, the direction of movement imparted to each box being opposite to that imparted to other boxes of the series, said means interconnecting all of said boxes for simultaneous actuation.

25 9. A suction box assembly for Fourdrinier paper making machines comprising a series of suction boxes, a pair of supporting members attached to the ends of each box, each member being mounted for movement in an endless path 30 about a fixed axis and operating means for so moving said members, the arrangement being characterized by the fact that the supporting members of the various boxes are interconnected by the operating means so as to be simultaneously actuated thereby.

35 10. A suction box assembly for paper making machines comprising a series of suction boxes, a pair of supporting members attached to the ends of each box, each supporting member being movable in a continuous path about a fixed axis in a direction opposite to the movement of the companion member and also opposite to the direction of movement of the corresponding supporting members of adjacent boxes and means 45 for so moving said members.

11. A suction box assembly for Fourdrinier paper making machines comprising a series of suction boxes and means for simultaneously moving all of said boxes back and forth across the sheet forming wire at a continuously changing angle with respect to said wire, said means 50 being characterized in that the opposite ends of each box are each moved in a continuous path

about a fixed axis in a direction opposite to the direction of movement imparted to the companion end and also opposite to the direction of movement imparted to the corresponding ends of other boxes of the series. 80

12. A suction box mounting comprising a pair of supporting pins attached to the ends of the box, a pair of rotatably mounted sleeves eccentrically apertured to provide pin receiving bores in which said pins are mounted and means for rotating said sleeves. 85

13. A suction box mounting comprising a pair of supporting pins attached to the ends of the box, a pair of sleeves eccentrically apertured to provide pin receiving bores in which said pins are rotatably mounted and means for rotating said sleeves. 90

14. A suction box mounting comprising a pair of supporting pins attached to the ends of the box, a pair of rotatably mounted sleeves eccentrically apertured to provide pin receiving bores in which said pins are mounted to rotate, anti-friction bearings supporting the pins in said bores, and means for rotating said sleeves. 95

15. A suction box mounting comprising a pair of supporting pins attached to the ends of the box, a pair of sleeves eccentrically apertured to provide pin receiving bores in which said pins are mounted and means for rotating said sleeves in opposite directions. 100

16. A suction box assembly for Fourdrinier paper making machines comprising a series of suction boxes positioned beneath the sheet forming wire, a pair of supporting pins attached to the ends of each box, a rotatably mounted sleeve 110 associated with each pin, said sleeve being eccentrically apertured to provide a pin receiving bore in which the pin is mounted and means for simultaneously rotating all of said sleeves.

17. A suction box assembly for Fourdrinier paper making machines comprising a series of suction boxes positioned beneath the sheet forming wire, a pair of supporting pins attached to opposite ends of each box, a sleeve associated with each pin, said sleeve being eccentrically 120 apertured to provide a pin receiving bore in which the pin is mounted and means for simultaneously rotating all of said sleeves including provision for causing the companion sleeves associated with each box to rotate in opposite directions with respect to one another. 125
